9 Claims. (Cl. 209—110)

1

This invention relates to record controlled machines and more particularly to that type of machine which has become known as a collator.

The primary object of the present invention is to provide a novel comparing mechanism capable of comparing alphabetical data and suitable for use in collators and other record controlled machines.

An object is to provide a comparing mechanism which does not require that the machine be specially plugged for an alphabetic comparing operation. In other words, it functions automatically to compare alphabetically merely from the fact that the cards sensed contain alphabetical data in the fields compared.

An object is to provide a comparing mechanism which may be readily added to existing machines without mechanical change in the machine and requiring only the addition of a bank of relays and a minor change in the timing such as may be readily accomplished in the field.

An object is to provide an alphabetic comparing mechanism which comprises supplementary relays which may be used in conjunction with the standard commercial comparing mechanism with no mechanical change therein, but merely a re-wiring of the contacts, such as may readily be accomplished in the field.

An object is to provide a comparing mechanism for alphabetical data which does not require extensive alteration in the machine or its circuits to install the comparing mechanism.

Other objects of the invention will be pointed out in the following description and claims and illustrated in the accompanying drawings, which disclose, by way of example, the principle of the invention and the best mode, which has been contemplated, of applying that principle.

In the drawings:

Figs. 1A and 1E comprise a wiring diagram of the machine.

Fig. 2 is a vertical section.

Fig. 3 is a vertical section through the mechanical comparing mechanism.

Fig. 4 is an electrical timing chart.

Fig. 5 is a mechanical timing chart.

Fig. 6 is a plugboard chart.

Fig. 7 is a detail view of the hopper contacts.

The invention is shown in the drawings as applied to the well known "International" collator which is disclosed in Patent No. 2,379,828. Since the present invention contemplates only a minor change in the mechanical structure of the machine and does not contemplate any change in the mode of operation of the machine in respect

2

to the manner in which cards are merged or selected, only a very brief general description of the mechanical construction of the machine will be given and for further details reference may be had to the above patent. It will be understood that the disclosure herein is purely illustrative and that the invention is not limited in its application to the specific type of machine selected for illustration.

Basically, the machine comprises two card hoppers of which PH (Fig. 2) is commonly termed the primary hopper and SH the secondary hopper. In the ordinary use of the machine, the file of cards is usually placed in the hopper PH and the cards to be filed in the hopper SH, all according to the type of operation to be effected and in accordance with the teachings of the above patent. It will be understood here that the general function of the machine is the same as in the above patent and the only change in the operation of the machine is in the functioning of the comparing mechanism which, according to the present invention, is made additionally capable of comparing alphabetical data besides numerical data. Accordingly the present description will deal primarily with the comparing functions of the machine and it will be understood that the machine is capable of performing the same operations as in the above patent with the exception of some of the card counting operations which do not involve the treatment of cards alphabetically.

So far as possible the reference numerals herein will correspond to those in the above patent to facilitate reference thereto in ascertaining the mode of operation or structural features which it is not deemed necessary to describe in detail herein.

Each of the hoppers SH, PH is provided with the usual card picker 125a (Fig. 2) which is operative at the proper time to push the bottom card in the hopper to the left far enough to be gripped by the feed rollers 171, 176. The cards are carried by the feed rollers 171, 176 to the feed rollers 184, 187, past the primary and secondary card lever contacts PCL and SCL, respectively. Thence the cards are carried past the primary brushes PB1 and the secondary brushes SB1 which cooperate with the contact rollers PCRL, SCR, respectively. Slotted feed rollers 201 cooperating with these contact rollers further advance the cards to the feed rollers 184, 187, in the case of the primary cards, and the feed rollers 208, 209 in the case of the secondary cards. The primary cards are additionally carried past

the primary brushes PB₂ and the contact roller PCR₂ before being delivered to the feed roller 288 which cooperates with a feed roller similar to the feed roller 288. It will be seen that the primary cards from hopper PH are analyzed twice by the brushes PB₁, PB₂, while the secondary cards are analyzed only once, prior to arrival at the feed rollers 286, 288, 289.

Additional card lever contacts are provided for detecting the passage of the cards past the contact rollers PCR₁, PCR₂, SCR, and are designated PCL₁, PCL₂ (Fig. 1A) and SCL₁, respectively. The machine is provided with three sorting blades designated 306, 307, 308, of which the first two control the distribution of cards to three of the four receiving pockets with which the machine is provided, while the blade 308 controls the distribution of the primary cards to the pockets PRJ and MS (Fig. 2). Besides the pockets MS and PRJ the machine is provided with the secondary reject pocket and a pocket for the selected primaries which pockets are designated SRJ and SP in the patent.

The blade 308 is controlled by the magnet SRM₁ (Fig. 2) while the blade 307 is controlled by a similar magnet SRM₂ not shown in Fig. 2 but appearing in Fig. 1B. The blade 308 is controlled by magnet PRM (Figs. 1B and 2). The hoppers SH and PH are provided with the hopper contacts designated SHC and PHC (Figs. 1A and 7) which are closed whenever cards are placed in the respective hoppers. The distribution of the cards after they pass the feed rollers 286 to 289 is controlled by the magnets SRM₁, SRM₂, PRM and an eject magnet EM (Fig. 1C) which controls a clutch rendering the feed roller 286 effective to feed a primary card over or underneath the blade 308 according to whether or not the magnet PRM is energized. These magnets function for the different operations in exactly the same manner as described in the patent.

The present invention contemplates the provision of a system of relays which is operative, in conjunction with the usual mechanical comparing mechanism ordinarily used for numerical comparing, to effect alphabetical comparing. The mechanical construction of the comparing mechanism is substantially the same as in the above patent and differs therefrom only in respect to the construction of the contacts which denote the numerical relationships and the manner in which these contacts are wired in the comparing circuits.

The comparing mechanism is shown in Fig. 3 and comprises two comparing devices as in the above patent. One of these comparing devices is usually termed the primary sequence unit and involves the comparing magnets PM₁, PM₂ while the other unit is termed the selector unit and involves the comparing magnets SM₁, SM₂. The mechanical construction of these units is identical and Fig. 3 of the drawings illustrates both with the magnets alternatively designated. Only a very brief description will be given of the structure of the comparing units.

Each comparing unit ordinarily comprises sixteen positions, giving a comparing capacity of sixteen columns on the record cards. Associated with each column is a pair of magnets PM₁, PM₂ for the sequence unit or SM₁, SM₂ for the selector unit whose armatures 378 normally latch pawls 376 in the position shown in dotted lines in Fig. 3, clear of the comparing sectors 373, 374. The sectors 373 are associated with magnets PM₁ or SM₁ and the sectors 374 with magnets PM₂ or SM₂ and they are connected by spring 385 with the operating balls 383, 384, which springs tend

to compel the sectors 373, 374 to follow said balls in their oscillations by a cam 370, there being a pair of balls 383, 384 and a pair of cams 370 in each unit.

5 Each sector 373, 374 has nine tooth spaces designated with the small numerals 1 to 9 in Fig. 3 which represent the various digital positions in which the sectors may be stopped by the pawls 376 according to the time of energization of the comparing magnets PM₁, PM₂ or SM₁, SM₂. The comparing magnets are usually plugged to the brushes PB₁, PB₂, SB, whereby the magnets PM₁, PM₂, and SM₁, SM₂ are impelled, in accordance with the well known Hollerith principle, at times in the cycle corresponding to the positions of the holes designating digits in the columns of the cards compared. This feature is well known in the art and very fully explained in the above patent.

20 The balls 383, 384 are controlled by restoring magnets designated PR₁, PR₂, PR₃, and SR in Fig. 1C. Once the sectors 373, 374 have taken settings to correspond with the digits 1 to 9 punched in the card, the settings are retained in the comparing mechanism until the balls 383, 384 are rendered operative by energization of the corresponding restoring magnets PR₁, PR₂, PR₃, SR.

25 Each pair of sectors 373, 374 is pivotally slidably interconnected by a link 398 (Fig. 3) which is slotted at its ends and at its middle is provided with a pivot stud 399 slidable in a horizontal straight slot 400a in a fixed guide plate 400 and also extends into a cam slot 401a in the contact operating member 401. The cam slot 401a in the member 401 is so shaped that, when both sectors 373, 374 occupy identical numerical positions, the pin 399 will lie in the middle or inclined part of the slot 401a in member 401, holding said member in a neutral position to signify that the compared digits are equal in value. This condition is illustrated in Fig. 3 in which both of the sectors 373, 374 have been set to represent the digit 9. If the upper sector 373 were to be moved one step further in a clockwise direction to represent 8, the pin 399 will move to the right, owing to link 398 being rocked clockwise about the pivotal connection to the lower sector 374, and will cam the member 401 upwardly to indicate the fact that the digit entered under control of the magnet SM₁ or PM₁ is lower in value than the digit entered under control of the related magnet SM₂ or PM₂. Similarly, if the lower sector 374 is moved one step clockwise, the pin 399 will move to the left and cam member 401 downwardly to indicate that the digit entered by magnet SM₂ or PM₂ is the smaller.

30 The member 401 operates two sets of transfer type contacts which are designated 412a, 412b, 413a, 413b in the case of the selector unit (Figs. 3 and 1D) and 412c, 412d, 413c, 413d in the case of the primary sequence unit. When the members 401 of the selector unit move to the upper dotted position signifying low secondary, the contacts 413a open and 413b close but contacts 412a, 412b are not disturbed. Similarly, in the sequence unit, the contacts 413d open and 413c close to indicate that the second of two successively fed primary cards is lower than the first. On the other hand, contacts 412a open and 412b close in the selector unit when the primary card is lower than the secondary card and 412d open and 412c close in the sequence unit when the second primary card is high. The foregoing assumes for convenience of description that the selector unit has been plugged to compare each

primary card with a secondary card and each primary card with a succeeding primary card, otherwise the designations of numerical relationships are arbitrary and depend upon which half of either unit may be selectively plugged for a particular function or operation. Since neither the selector unit nor the sequence unit is permanently wired to the card sensing brushes, the comparing units may be used interchangeably or may be used together to give a combined comparing capacity of thirty-two columns. The various ways in which this may be done is made clear in the patent and will not be reviewed herein.

The contacts 412a to 412d and 413a to 413d are the full equivalents of the comparing unit switch structures disclosed in Figs. 9 and 9a of the above patent and their effect is exactly the same.

In commercial practice alphabetical data is represented by combinations of two holes per column, one of which holes, called the zone hole, is placed in the 0, 11, and 12 positions, while the second hole, called the numerical hole, occurs in the 1 to 9 positions. The following table shows the commercial code, the numbers following the letters designating the hole positions of a single card column:

Table.—The alphabetical code

A—12, 1	J—11, 1	S—0, 2
B—12, 2	K—11, 2	T—0, 3
C—12, 3	L—11, 3	U—0, 4
D—12, 4	M—11, 4	V—0, 5
E—12, 5	N—11, 5	W—0, 6
F—12, 6	O—11, 6	X—0, 7
G—12, 7	P—11, 7	Y—0, 8
H—12, 8	Q—11, 8	Z—0, 9
I—12, 9	R—11, 9	

For the purpose of effecting alphabetical comparing there is provided, in addition to the usual mechanical selector units described above controlled by the magnets PM1, PM2, SM1, SM2, a system of relays including relays capable of storing in the machine for purposes of comparison the 0, 11, and 12 designations (zone holes) and of using these stored designations in conjunction with the numerical part of the code as stored in the mechanical comparing mechanism.

It will be noted by reference to the table that the alphabet is divided into three sequential groups in each of which groups the sequence of the characters in each group is denoted by the numerical part of the code, that is, the hole positions 1 to 9. The sequence of the groups is denoted by the inverse order of the 0, 11 and 12 positions. Thus, the group containing A is differentiated from the group containing J by the fact that each letter in the A group has a 12 hole while the J group has an 11 hole. The A group is differentiated from the S group by the fact that the S group contains a 0 hole, while the J group is differentiated in sequence from the S group by 11 holes. In other words, in comparing a card designated A in a particular column with a card designated J, the A is lower in sequence because the zone hole for this card is higher than the zone hole for the J card. Thus, a 12 hole in a comparing column dominates over an 11 hole or a 0 hole and an 11 hole dominates over a 0 hole.

It will be noted in the table that there is no code combination 0 and 1 but this combination may be reserved for a special character or simply one which has no sequence significance. Ad-

vantage is taken of the foregoing characteristics of the code to differentiate the different letters of the alphabet from each other in respect to alphabetical sequence.

For this purpose, there is provided, in addition to the comparing magnets SM1, SM2, PM1, PM2, a group of three set-up zone relays like the ones designated SR0, SR11, and SR12 (Fig. 1A) associated with each comparing magnet. In Fig. 1A only the groups associated with the sixteenth or highest order positions of the comparing mechanism are shown in order to avoid confusion on the drawing. Since there is a total of 64 comparing magnets in the commercial machine it will be understood that there will be 64 groups like the relays SR0, SR11, SR12 which are associated with magnets SM1. In the case of the magnets SM2 the relays are designated PR0, PR11, PR12 while the relays corresponding to the magnets PM1, PM2 are designated IPR0, IPR11, IPR12 and 2PR0, 2PR11, 2PR12, respectively.

When each comparing magnet, such as the magnet SM1, for instance, is plugged to one of the card sensing brushes in the usual way, the corresponding groups of relays SR0, SR11, SR12 is likewise automatically plugged at the same time. The coils of the relays SR0, SR11, SR12, PR0, etc. are not directly connected to the plug sockets PS4 to PS1, for the magnets SM1, SM2, PM1, PM2, but are connected thereto through the contacts A of zone selection relays designated ZR0, ZR11, ZR12, of which there are three. The contacts A of the relay ZR0 are arranged so that when they close they connect the coils of all of the relays designated SR0, PR0, IPR0, and 2PR0 to the plug sockets PS4, PS5, PS6, and PS7 corresponding to the comparing magnets SM1, SM2, PM2, PM1, respectively. Similarly the contacts A of relays ZR11, ZR12 connect the coils of the relays SR11, SR12, PR11, PR12, IPR11, IPR12, 2PR11, 2PR12 to the plug sockets corresponding to magnets SM2, PM1, PM2. The relays ZR0, ZR11, ZR12 are energized momentarily once per cycle, at the 0, 11, and 12 points (Fig. 4) in succession by the timing contacts CR10, CR11, CR12 (Fig. 1A). In order to understand the operation of the relays mentioned above, let it be assumed for the moment that the sixteenth position magnet SM1, denoted by the small number 16 appearing above the magnet in Fig. 1A, is plugged to one of the plug sockets SP1 so that impulses of current may be transmitted to the sixteenth position magnet SM1 through a hole in the card column sensed by the particular brush SB selected. Let it be assumed that there is an 11 hole in the column under consideration.

When the selected brush SB senses the 0 index-point position in the card the contacts A of relay ZR0 (Fig. 1A) will be closed by the energization of the relay ZR0 arising from the closure of contacts CR10 (Fig. 4). However, there is no 0 hole in the card and relay SR0 will not be energized. Due to the hole in the 11 position, however, relay ZR11 will close its contacts A about the time the brush finds the 11 hole in the card and will cause the energization of the relay SR11 in parallel with magnet SM1 for position 16. The relay SR12, like relay SR0, will not be energized when contacts CR12 energize the relay ZR12. Thus, the 11 zone hole in the column under consideration will in effect be set up in the machine by energizing the relay SR11. When the relay SR11 is energized it closes its contacts A and establishes

a brief holding circuit for itself from line wire W1 to the wire W4 (Fig. 1A) through commutator SC2 (Fig. 1B) to line wire W2. The commutator SC2 (Fig. 4) holds the circuit until the end of the cycle.

In a similar manner relays PR0, PR11, PR12, (PR8, (PR11, etc. store zone holes in the columns compared by magnets SM2, PM1, PM2.

The relays SR0, SR11, SR12, PR0, PR11, PR12, etc. each have two additional sets of contacts designated B and C which are arranged as shown in Fig. 1E. For each position of each comparing unit there is a pair of relays for denoting the sequential relationship between the zone holes in two columns which are compared. In a case of the selector unit, the pair of relays is designated LPR, signifying low primary relay, and LSR designating low secondary relay. In the case of the fifteenth and sixteenth positions, of the selector unit, for example, these relays are designated LPR16, LPR15, LSR16, LSR15 (Fig. 1E). Only the circuits for the relays LPR16, LSR16 for the sixteenth position of the selector unit are shown in Fig. 1E but it will be understood that the wiring is duplicated for the other fifteen positions and have associated with them the same number of relay contacts wired in the same fashion as illustrated by the pair of comparing circuits enclosed in the dotted rectangle captioned "Selector unit" (Fig. 1E).

Similarly, for the sequence unit there is a pair of relays for each comparing position designated 2PHR, 2PLR, denoting second primary high relay and second primary low relay. These relays are differentiated from each other in the different orders by the suffix numbers 1 to 16. Only two complete comparing circuits for the relays 2PHR16 and 2PLR16 are shown in Fig. 1E within the dotted rectangle captioned "Sequence unit." As in the case of the selector unit, the set of six circuits shown in Fig. 1E in the dotted rectangle is duplicated for each of the other relays designated 2PHR1 to 2PHR15 and 2PLR1 to 2PLR15.

In order to understand the operation of the selector unit in differentiating cards according to the zone holes punched thereon, it will be assumed for the moment that the magnets SM1, SM2 for position 16 in Fig. 1A are plugged to selected plug sockets PS1, PS2, respectively, to compare a column on a primary card with a column on a secondary card (see Fig. 6 also).

Let it be assumed that the primary card is punched A, represented by the combination of a 12 hole and a 1 hole, and that the secondary card is punched J involving the combination of an 11 and a 1 hole. At the 11 point in the cycle, the position 16 magnet SM1 of the selector unit will be energized but will have no effect. At the same time the relay SR11 will be energized in consequence of the closure of contacts A of ZR11 and the holding circuit for relay SR11 will be held by the commutator SC2 as described above. This stores the "11" hole temporarily. At the 12 point in the cycle the magnet SM2 for the sixteenth position of the selector unit also will be idly energized and at the same time the relay PR12 corresponding to that position will be energized and held by contacts PC2 thereby storing the "12" hole. Thus, at the 12 position in the cycle the relays PR12 and SR11 will have been energized to represent the 12 and 11 holes in the primary and secondary cards, respectively. The relays PR12, SR11 close their contacts B and C.

By examining Fig. 1E, it will be noted that of the two sets of three parallel circuits involved in

the circuits through the relays LPR16, LSR16, only one circuit can be completed since only relays PR12, SR11 are energized. This circuit is traced from line wire W1, through low primary relay LPR16, contacts C of relay SR11 and C of relay PR12, and contacts CR8 (Fig. 1C), to line wire W3. The energization of the relay LPR16 denotes the fact that in the sixteenth position of the selector unit the primary card punched A is lower in sequence than the secondary card punched J and of itself is sufficient in this example to determine the sequence relationship of the cards, it not then being necessary to determine what the relation is between the holes punched in the 1 to 9 positions which, in the present case, both happen to be 1 holes. Any card punched from A to I will dominate a card punched from J to R, since the 12 hole always dominates an 11 hole.

20 The contacts of the relays LPR16, LSR16 are inserted in a circuit with the contacts 412a, 412b and 413a, 413b for the sixteenth position of the mechanical part of the comparing unit in the manner shown in Fig. 1D. Since only the relay 25 LPR16 was energized, the contacts B of relay LPR16 will close and contacts A open, thereby preventing any possibility of closing an equal circuit through the selector unit and closing the low primary function selection circuit as follows: 30 Line wire W1, low primary relay R22, the contact A of relay R38, low primary plug socket PS37, contacts B of relay LPR16, the plug wire between plug sockets PS43, PS44, wire W3 contacts CR2 (Fig. 1C), and relay contacts R17, 35 which are closed when the machine is in operation under normal conditions to line wire W2.

The energization of the relay R22 manifests the fact that the card punched A is first in alphabetic sequence since position 16 is the highest order corresponding to the initial letter of a name, and the machine will be controlled in any of the manners described in the foregoing patent which involve the use of the basic setup controls which are responsive to the relays R22, R23, R24. In the event that plug socket PS37 is plugged for a special control, then the circuit will go through the plug wire in parallel with the energization of the relay R22 and will effect whatever function depends upon the low primary condition.

40 In a simple setup of the machine shown in the plugboard diagram (Fig. 6) the plug socket PS37 is plugged to the primary reject magnet PRM which cause the card punched A to be deposited in the pocket PRJ. In Fig. 6 the sixteenth position magnet SM1 to which corresponds the extreme left hand plug socket PS4 in Fig. 6 is connected by a plug wire to the plug socket PS1 corresponding to the secondary brush SB for column 24. Similarly, the plug socket PS5 after the sixteenth magnet SM2 is connected to plug socket PS2 for brush PB2 corresponding to the column 24 of the primary card.

The same situation could have happened in the sequence unit in comparing column 24 of two successive primary cards. For example, the first 65 of two primary cards might be punched A and the second J involving a 12 hole and an 11 hole, respectively. Under these conditions the sixteenth position magnet PM2 and the relay (PR12 will be energized under control of the 12 hole in the first primary card and the sixteenth position magnet PM1 and relay 2 PR11 will be energized under control of the 11 hole in the second primary card.

70 With reference to Fig. 1E it will be noted that only one circuit can be established in the se-

quence unit to energize relay 2PHR16 through the contacts C of relay 2PR11 and C of 1PR12. With reference to Fig. 1D the energization of relay 2PHR16 indicates that the second primary card is high and the closure of contacts B of the relay 2PHR16 causes the relay R25 and any function connected to plug socket PS40 to be selected in the same manner as relay R22.

With reference to Fig. 6 it will be noted that plug socket PS40 has not been plugged and only the normal function of the relay R25 to control feeding of the cards will prevail. Since the basic setup control is shown plugged "on" in Fig. 6, the effect of the energization of relay 25 will depend upon the energization of the equal relay R23 which denotes when the primary and secondary cards under comparison are equal. In the present case the operation of the machine with the plugging arrangement shown in Fig. 6 will be exactly the same as in the case of the plugging arrangement shown in Fig. 21A of Patent No. 2,379,828, designated "merging with selection of unmatched secondary cards." The only difference in the present case will be that the merging and selection of the cards will be on an alphabetical sequence basis rather than a numerical basis. In other words, the cards inserted in the primary and secondary hoppers will be an alphabetical order instead of numerical order. The only difference between the two types of operation will be in the manner in which the comparing mechanism functions.

In respect to the functioning of the machine as to the mechanical part of the comparing unit, the numeral 1 will be entered into both sides of the comparing units under both of the assumed conditions above and, so far as the sectors 373, 374 for the sixteenth positions of either unit are concerned, the contacts 413a, 413d, 412a, 412d will remain closed, but as pointed out above with reference to Fig. 1D, the opening of contacts A of the relay LPR16 and 2PHR16 makes it impossible to send either a low secondary or a low second primary or an equal circuit through the comparing units. In other words, owing to the disposition of the alphabetical comparing control contacts A and B of relays LPR16, 2PHR16, LSR16, 2PLR16 ahead of the corresponding contacts 412a to 412d and 413a to 413d for position 16 cause the alphabetic zoning holes to dominate over the numerical holes and determine the selection of the A card.

In each order or position, the relays LPR, LSR, and 2PHR, 2PLR are placed ahead of the corresponding contacts 412a to 412d and 413a to 413d for that order.

In the above two illustrations, if the secondary card had been punched A and the primary card punched J, or the second primary card punched A and the first primary card punched J, the conditions would be reversed as then the relays SR12, PR11 and 1PR11 and 2PR12 will be energized.

With reference to Fig. 1E, it will be seen that the relay LSR16 or 2PLR16, as the case may be, will be selected through the contacts C of relay SR12 and B of relay PR11, in the case of the selector unit, and through contacts C of relay 2PR12 and B of 1PR11, in the sequence unit.

In the event two cards are punched alphabetically alike, the zoning holes 0, 11 or 12, as the case may be, will be alike on both the cards which are compared and the numerical holes will also be alike. Under these conditions none of the relays SR0, SR11 and SR12, etc. in Fig. 1E can have any effect because the contacts B and

C of relays SR11, for example, are not in circuit with any of the contacts of relays PR11, thus preventing any energization of the relays LPR16, LSR16. The contacts A of these relays (Fig. 1D) remain closed and, since the numerical holes are also the same, an equal circuit can be transmitted through the contacts 412a, 413a to the remaining orders of the comparing unit. Of course, it may happen that the highest orders or positions may be punched alike and some lower order be punched unlike, in which case the nearest order in which there is a difference will dominate over the remaining lower orders exactly as in the case of simple numerical comparison as described in the patent.

There is one further condition which must be satisfied, that is the case where two compared cards belong in the same zone group. For example, in comparing A with B, it is necessary that the numerical comparison determine the selection, since both cards will be punched 12 in such case and will differ only in that the A card will be punched 1 and the B card punched 2. In this case, the contacts A of the relays LPR16, LSR16 or 2PHR16, 2PLR16, according to which selector unit is involved, will remain closed, but one or the other of the contacts 412b, 413b, in the case of the selector unit, or 412c, 413c in the case of the sequence unit will close to select one of the relays R22, R24 or R25, R27, depending upon which card has the 2 hole. Under these conditions the comparing unit functions in the same manner as it does in numerical comparison to differentiate the A card from the B card.

The foregoing description has been confined to the sixteenth position simply as a matter of convenience of description. It might have happened, for example, that positions 12 to 16 of the selector unit are punched alike in both cards but that the eleventh position is the first in which a difference is noted. In this case, the circuit is traced up in Fig. 1D through the higher orders, beginning with the contacts A of the relays LSR16, LPR16, contacts 413a and 412a, thence to contacts A of relay LSR15, LPR15, etc., to the contacts A or B of the relays LSR11, LPR11.

It will be noted by careful study of the table that there are nine possible comparing conditions which must be satisfied in the comparing units. Of these, three are equal conditions in which the two cards compared both are punched 12, 11, or 0, respectively. These three cases are taken care of by arranging the contacts of the relays LPR1, LSR1, etc., in the case of the selector unit (Fig. 1E), and 2PHR1, 2PLR1, etc., in the case of the sequence unit, so that the equal circuit normally exists in the respective comparing units until changed by closure of an unequal circuit. Thus, normally the relays R23, R26 (Fig. 1D) will be selected unless the cards are unequal.

Now, with respect to any two compared cards, there are three possible low conditions as to one card and three different low conditions as to the other card. These conditions represent different combinations of relationships between the zone holes and are as follows: 12, 11; 12, 0; and 11, 0. If the 12 or 11 hole occurs in the primary card, then one of the relays LSR1 to LSR16 will be energized to denote the fact that the secondary card is low. These three possible conditions are represented, in each comparing position of the secondary side of the selector unit by the three circuits connected in series parallel to the relay LSR16 in Fig. 1E. It will be noted, for example, that the 12, 11 combination is set

tip in the comparing unit by the energization of the relays SR12, PR11. The opposite three conditions are taken care of by the three parallel circuits through the relay LSR16. Thus, the 12, 11 combination is taken care of by energization of the relays SR11, PR12.

It will be seen that for each comparing position or order of the selector unit a circuit will be set up through one or the other of the relays as, for example, LPR16, LSR16, through one of the six circuits associated with that position, corresponding to the six possible unequal relations of the zone holes. In Fig. 1E the three circuits associated with the sixteenth position of the selector circuit which take care of the three possible low primary conditions are designated LOW PRI, while the three which take care of the low secondary condition are marked LOW SEC.

It will be noted in Fig. 1D that the relays LSR16, LPR16 are arranged with their contacts ahead of the numerical comparing contacts 412a, 412b, 413a, 413b in order that the zone holes in the card may dominate over the numerical holes for the same column and prevent a false comparison being made when the zone hole on one card is high with respect to the other, while the numerical hole is low. This may happen, for example, in comparing the letter I, calling for the combination of 12, 9 in the table, with the letter J, represented by the combination 11, 1. If contacts of the relays LSR16, LPR16 were placed above the sixteenth position contacts 412a, 412b, 413a, 413b, the latter would be able to close circuits to one or the other of the relays R22, R24 and dominate the relays LSR16, LPR16, which, of course, is an undesirable condition. The only case where it is desired that the numerical comparing mechanism determine the selection is where both the zone holes in the compared cards are the same and the question is one of differentiating cards within one of the sequential groups A to I, J to R, or S to Z.

Since the normal flow of current in controlling the selections in accordance with card comparisons is "In" at the plug sockets PS43, PS45 and upwardly to the line wire W1 (Fig. 1D), it is apparent that the foregoing results are achieved. It will be understood, of course, that it is not the actual direction of current flow that is important, but the relative order in which the contacts of the relays and numerical comparing mechanisms are arranged. With the arrangement of the wiring as shown in Fig. 1D, the highest orders or positions of the comparing units are at the bottom and each dominates over the next order above in effecting inequality selections.

So far as the comparing mechanism is concerned, it is always ready to compare either numeral or alphabetical cards provided the plug wire connections between the plug sockets 184, 186, 188, 190 remain undisturbed. These plug wire connections are provided, not for the purpose of rendering the alphabetical comparing feature operative, but to make it possible to disable the alphabetic comparing feature when numerical comparison is being effected in fields which may be double-punched with control holes in the 11 and 12 positions, as sometimes happens. For example, very often a hole is placed in the 11 or 12 positions of a particular column of a field devoted to numerical data to denote some special fact which may or may not have any significance as far as the data punched in that numerical field happens to be concerned.

An illustration is the practice which has been resorted to in the past of punching 11 and 12 holes in amount fields to denote debit and credit, with respect to the amounts punched in such fields. While it is not likely that 11 and 12 holes will usually be placed in the same columns as numbers most likely to be compared, such as serial numbers or account numbers, which are most used for comparison, it may occasionally happen that this is necessary, owing to insufficient capacity of the card. If such a card were passed through the present machine with the wiring made permanent between the relays SR0, SR11, SR12, PF0, etc. and the line wire W1, the machine would automatically effect an alphabetical comparison of numerical data which, of course, would be meaningless in such a case. The plug wires between the plug sockets PS184, PS186, PS188, PS190 make it possible to disable the alphabetical comparing feature for the rare occasions where a false comparison would result from the incidental comparison of 0, 11 and 12 holes which have no true comparative meaning. In the ordinary use of a machine, however, these plug connections will remain undisturbed so that the machine is always in readiness for alphabetical comparison and is rendered effective solely by the type of data compared.

It was mentioned above that when the 0, 11, and 12 holes are sensed by the card sensing brushes the magnets of the selector unit will be energized idly. While the brushes are traversing the 1 to 9 positions of the card the magnets will be energized according to the positions of the numerical holes in the code and in every case the magnets will receive the second zone energization after the sectors 373, 374 have been set numerically. However, when a comparing magnet has tripped its related pawl 376, which may occur anywhere between 9 and 0, a second energization of the magnet during the same cycle merely results in idle vibration of the related armature 378 without effect as it is impossible to make a new setting between the 0 and 12 points of a cycle or change the setting arising from the first energization of the magnet before the balls 383, 384 have become operative to restore the sectors 373, 374 to starting position. In a case where a card is only numerically punched and only numerical comparison is desired, the absence of 0, 11 and 12 holes in the columns compared will simply mean that the relays SR0, SR11, SR12, etc. will remain unenergized, although the zoning relays ZR0, ZR11, ZR12 operate every cycle of the machine. But on the occurrence of an alphabetical card the relays are automatically energized merely in consequence of the presence of the zone holes. Thus, it is unnecessary to specially plug the machine to condition it for either alphabetical or numerical operation and the only plugging is the normal plugging to connect the brushes to the comparing magnets.

The majority of the operations described in Patent 2,379,828 which involve the use of the sequence or selector unit to compare the relative sequential value of two cards may be performed with the alphabetic comparing mechanism described herein, provided the cards first are arranged in alphabetical order or selected according to an alphabetical preference of some kind. Such operations include sequence checking, either alone or in combination with other operations; matching, merging, and selection operations in which the cards are arranged in

alphabetical order and are to be filed or matched alphabetically instead of numerically; and various operations in which the selection or control is effected solely on the basis of the relationship one card bears to the other in a sequence sense.

While there have been shown and described and pointed out the fundamental novel features of the invention, as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a machine of the class described, two sets of electrical sensing elements, each set for sensing the index-point positions of the columns of one of two records to be compared for alphabetical sequence, each letter of the alphabet being represented in said records by a combination of two designations in a single column of index-point positions, each column having a series of zonal index-point positions representing a series of sequential groups of the alphabet in one of which zonal index-point positions one of said two designations is placed to designate the sequential group containing the designated letter, each column also having a series of numerical positions for denoting the sequence of a designated letter within its sequential group, the second of said two designations being placed in one of the numerical positions; a system of storage relays including a series of relays for each column of the records under comparison, each relay corresponding to one of the zonal index-point positions and selectively energized under control of the sensing means when the corresponding zonal index-point position of a record column contains a designation, the two series of relays corresponding to each pair of compared columns and having their contacts connected in a series of comparing circuits, each circuit including in series the contacts of two different storage relays to represent one of the possible zonal comparison relations between two zonal designations, said circuits being divided into two groups, the comparing circuits in each group in parallel, one of said groups corresponding to all of the comparison relations when a predetermined one of two compared records is low in sequence and the other group corresponding to all of the comparison relations when the other compared record is low; a pair of sequence relays for each pair of compared columns, each controlled by one of said groups of circuits; and numerical comparing mechanism including comparing sectors set to represent the values of the numerical designations in the compared columns and including a series of selective switching means, each for manifesting the sequence relation of two compared columns in respect to the numerical designations in such columns, said switching means and the contacts of said sequence relays being arranged in three series parallel circuits, one of which is closed by said switching means or said sequence relays when two compared records are equal and one or the other of the remaining circuits being closed when the compared records are unequal.

2. In a machine of the class described, two sets of electrical sensing elements, each set for sensing the index-point positions of the columns

of one of two record fields to be compared for alphabetical sequence, each letter of the alphabet being represented in said record columns by a combination of two designations in a single column of index-point positions, each column having a series of zonal index-point positions representing a series of sequential groups of the alphabet in one of which zonal index-point positions one of said two designations is placed to designate the sequential group containing the designated letter, each column also having a series of numerical positions for denoting the sequence of a designated letter within its sequential group, the second of said two designations being placed in one of the numerical positions; a system of zone storage relays controlled by said sensing elements and having contacts grouped in a plurality of series comparing circuits, each comparing circuit being closed when a particular combination of zonal designations occurs in a pair of columns of said fields, said grouped circuits representing all the different possible combinations of two zonal designations in a pair of compared columns; a plurality of sequence relays arranged in pairs, each pair corresponding to a pair of compared columns and in circuit with all the comparing circuits which correspond to combinations of designations of like sequence relation, one of said sequence relays being energized when one field is low in sequence in the related column and the other being energized when the other field is low; numerical comparing mechanism having two series of value representing sectors, one for each field, and magnetic means controlled by the sensing elements for setting said sectors to represent the numerical parts of the combinations of designations and including a series of switches, one for each pair of compared columns and actuated by a pair of said sectors to denote whether the designations in a pair of columns are equal or one lower than the other, said switches and the contacts of said sequence relays being arranged in three series parallel output circuits, each of which represents one of the high, low, and equal conditions of said compared fields.

3. In a machine of the class described, two sets of electrical sensing elements, each set for sensing the index-point positions of the columns of one of two fields to be compared for alphabetical sequence, each letter of the alphabet being represented in said record columns by a combination of two designations in a single column of index-point positions, each column having a series of zonal index-point positions representing a series of sequential groups of the alphabet in one of which zonal index-point positions one of said two designations is placed to designate the sequential group containing the designated letter, each column also having a series of numerical positions for denoting the sequence of a designated letter within its sequential group, the second of said two designations being placed in one of the numerical positions; numerical sequence comparing mechanism including two series of comparing members, one for each column of the field, each member differentially selectively settable to any one of a series of digital positions corresponding to the numerical index-point positions of one of said columns according to the position of the second designation in said column and including electromagnetically controlled means for setting said members under control of said sensing elements and also including a series of switching devices, one for

each pair of compared columns, for denoting the numerical sequence relation of the designations in said columns; two series of comparing relays, each series corresponding to one of said series of comparing members, one relay of each series corresponding to one of two compared columns for indicating which of two zonal designations in said compared columns is lowest in alphabetical sequence and having contacts interspersed in series parallel with the corresponding ones of said switching devices; and a plurality of sets of relay circuits, one set for each comparing relay, each circuit in a set being in series with the related comparing relay and including relays contacts closed to represent one of the possible combinations of zonal designations signifying that one of two compared columns is lower than the other and relay coils for actuating said contacts; and means controlled by the sensing elements for energizing said relay coils according to the combinations of zonal designations in said fields.

4. In a machine of the class described, two sets of electrical sensing elements, each set for sensing the index-point positions of the columns of one of two records to be compared for alphabetical sequence, each letter of the alphabet being represented in said records by a combination of two designations in a single column of index-point positions, each column having a series of zonal index-point positions representing a series of sequential groups of the alphabet in one of which zonal index-point positions one of said two designations is placed to designate the sequential group containing the designated letter, each column also having a series of numerical positions for denoting the sequence of a designated letter within its sequential group, the second of said two designations being placed in one of the numerical positions; means controlled by said sensing elements for separately storing the numerical designations, including two sets of members, each set-table to any digit represented by a numerical designation in a single column, switching means actuated by said members to denote the numerical relationship of the numerical designations on two compared records, a system of zone relays controlled by said sensing elements for storing the zonal designations on the two compared records, system zonal comparing relays for determining the relative sequence value of the stored zonal designations, a second switching means controlled by the zonal relays for manifesting which of two compared records is higher in sequence, and machine control means selected by joint action of both of said switching means for indicating which of two compared records is higher in sequence alphabetically.

5. In a machine of the class described, two sets of electrical sensing elements, each set for sensing the index-point positions of the columns of one of two records to be compared for alphabetical sequence, each letter of the alphabet being represented in said records by a combination of two designations in a single column of index-point positions, each column having a series of zonal index-point positions representing a series of sequential groups of the alphabet in one of which zonal index-point positions one of said two designations is placed to designate the sequential group containing the designated letter, each column also having a series of numerical positions for denoting the sequence of a designated letter within its sequential group, the second of said two designations being placed in one of the

numerical positions; electromechanical means controlled by the sensing element for comparing the sequential relation of the numerical designations in two records sensed by said elements, including a series of switching devices, one for each column, each device capable of manifesting that one record is higher, lower, or equal to the other in two compared columns; a series of storage relays controlled by the sensing elements for

10 storing the zonal designations on the compared records, comparing relays controlled by the storage relays for comparing the zonal sequence of the compared records, switching mechanism controlled by said comparing relays and comprising a series of switching sections interspersed with the switching devices, and machine control devices selected jointly by said switching devices and said switching sections according to the relative alphabetic sequence of the compared records.

6. In a machine of the class described, two sets of electrical sensing elements, each set for sensing the index-point positions of the columns of one of two records to be compared for alphabetical sequence, each letter of the alphabet being represented in said records by a combination of

25 two designations in a single column of index-point positions, each column having a series of zonal index-point positions representing a series of sequential groups of the alphabet in one of which zonal index-point positions one of said two designations is placed to designate the sequential group containing the designated letter, each column also having a series of numerical

30 positions for denoting the sequence of a designated letter within its sequential group, the second of said two designations being placed in one of the numerical positions; means for comparing the group sequential relation of the zonal designations on two records sensed by said elements including a system of storage relays controlled by the sensing elements for storing the zonal designations and a system of comparing circuits, said comparing circuits including high-low relays for each column and contacts closed by said high-low

45 relays; means for comparing the records for numerical sequence in said groups, including comparing magnets controlled by the sensing elements, members each differentially settable to represent any of the values of the numerical designations in one column, and a series of switching devices interspersed with the contacts of the high-low relays, each device actuated by the pair of members associated with two corresponding columns, for denoting which of two compared

50 designations is lowest in sequence; and machine control magnets selected either by said high-low relays or by said switching devices according to whether the zonal designations are unequal or if equal, which of the numerical designations is lowest.

55 7. In a machine of the class described, two sets of electrical sensing elements, each set for sensing the index-point positions of the columns of one of two records to be compared for alphabetical sequence, each letter of the alphabet being represented in said records by a combination of two designations in a single column of index-point positions, each column having a series of zonal index-point positions representing a series of sequential groups of the alphabet in one of which zonal index-point positions one of said two designations is placed to designate the sequential group containing the designated letter, each column also

60 having a series of numerical positions for denot-

65

70

75

ing the sequence of a designated letter within its sequential group, the second of said two designations being placed in one of the numerical positions; means for comparing two records for zonal sequence, including storage relays set by the sensing elements to store the zonal designations and a system of comparing relays including a pair of high-low relays for each pair of compared columns, one of said high-low relays denoting that a particular record is high in zonal sequence and the other that the particular record is low, the high-low relays having high-low contacts arranged in a denominational sequence; means for comparing the numerical designations for sequence in the zonal groups, including setting magnets controlled by the sensing elements, pairs of settable members, one pair for each pair of compared columns, one member for each column, and a series of denominational switching devices, each operated by a pair of said members, for denoting the numerical relationship of the designations in a pair of compared columns, said devices being arranged in a denominational sequence; and sequence denoting magnets selected by said high-low contacts and said switching devices.

8. In a machine controlled by records in which alphabetic data is recorded by means of combinations of zonal designations representing groups of characters in sequence and group sequence designations representing the sequence relation within a zonal group, zone storage relays for storing all of the zonal designations of two sets of alphabetic data and having contacts closed combinationally to represent all the possible high-low sequence relations between the zonal designations in the two sets of alphabetic data, a series of denominational sets of comparing relays, each set comprising a high relay and a low relay, the high relay being controlled by all of the high sequence contact combinations and the low relay being controlled by all of the low sequence combinations of a single denomination of alphabetic data, said comparing relays having sets of contacts arranged in denominational order groups, one group for each denomination, to correspond with the common denominations of the two sets of alphabetic data; group sequence comparing means including pairs of members for each denomination, each member of a pair being settable to correspond with any one of the group sequence designations which may represent a letter in such denomination, denominational switching devices, each actuated by a pair of said members and set

thereby to designate which of the group sequence designations of a corresponding denomination is lowest in sequence, and a series of sequence relation magnets jointly controlled by said comparing relay contacts and said denominational switching devices, one of said magnets being selected according to which set of alphabetic data is lowest in alphabetic sequence.

9. In a machine controlled by records in which alphabetic data is recorded by means of combinations of zonal designations representing groups of characters in sequence and group sequence designations representing sequence relation within a zonal group, two series of denominational groups of zone storage relays, each group corresponding to one denomination of two sets of alphabetic designations to be compared for alphabetic sequence relation, each storage relay corresponding to one of the different possible zonal designations, each denominational group being adapted for storing all of the zonal designations of one denomination of one of said sets of designations; each series of groups being adapted for storing all of the zonal designations of one of said sets of data, said groups being paired on a denominational basis, said pairs of groups actuating storage contacts arranged in two sets of high-low circuits representing all the possible unequal sequence relations; a series of pairs of high-low relays, one pair for each denomination, each pair including a high relay controlled by the high circuits and a low relay controlled by the low circuits and including high contacts and low contacts; group sequence comparing means including a series of pairs of members settable to different positions representing group sequence designations, each pair corresponding to a denomination of said sets of data; high-low switches in circuit with said high and low contacts and actuated by said pairs of members; and electromagnetic machine control means selected by said high-low contacts and said switching devices.
